Application May 21, 1954, Serial No. 431,316

10 Claims. (Cl. 271—44)

This invention relates to card processing equipment and more particularly to an improved card feed utilizing an oscillating rocker motion.

In accordance with the invention, a card hopper is provided with improved high speed card pickers which are oscillatable in an arc about an axis located adjacent a line projected from the rear edge of the stacked cards. When the card pickers are at their outermost limit of arcuate travel, the picker knives are disposed adjacent the rear edge of the stacked cards. On the forward stroke, the knives with the picked card are moved in an inward, slightly upward and then downward direction toward the forward portion of the hopper to translate the forward portion of the card to the first feed rollers for subsequent delivery to other card handling apparatus.

Projecting backwardly and downwardly from the trailing edge of each picker knife is a card stack supporting surface, so tapered as to remain within the arc described by the top edge of its respective oscillating feed knife. Thus, during the forward and reverse strokes, the supporting surface moves beneath the stack to support the same at a substantially uniform distance from the pivot axis. This reduces the tendency for the cards to bounce at high speed operation and minimizes the possibility of a card miss or failure to pick. In addition, since the support carries the weight of the cards for a portion of the stroke, picker knife wear is reduced.

Accordingly, it is one of the objects of the invention to provide an oscillatable card picker which is capable of translating cards at high speeds with a minimum number of card picking failures.

It is another object to provide a card picker which is capable of translating at high speeds cards having curl or warp in either direction across their widths.

It is still another object of the invention to provide an oscillatable card stack support and picker which reduces the card stack weight on the bottom card during a portion of the forward stroke.

It is yet another object to provide an oscillatable picker knife for a card stack which reduces stack bounce to a minimum.

It is another object to provide a card hopper and picker construction which reduces the possibility of injury to the operator when the picker is being oscillated with no cards in the hopper.

It is yet another object to provide an oscillatable picker knife with a movable card stack support therefor which reduces picker knife wear.

Other objects of the invention will be pointed out in the following description and claims and illustrated in the accompanying drawings, which disclose, by way of examples, the principle of the invention and the best mode, which has been contemplated, of applying that principle.

In the drawings:

Fig. 1 is a diagrammatic side elevational view of one form of card processing apparatus to which the improved card feed is applicable.

2

Fig. 2 is an enlarged vertical transverse sectional view of a card hopper showing the improved card picker and drive means therefor.

Fig. 3 is a partially exploded perspective view of the hopper and card feed mechanism with parts broken away to more clearly show the invention.

Fig. 4 is an enlarged detailed sectional view of the card feed head as shown in Fig. 2; and,

Figs. 5-10 are a series of diagrammatic views showing 10 a comparison of card bounce between a standard reciprocating type picker and the improved arc type picker.

Referring now to the drawings for a clearer understanding of the improved card feeding apparatus, there is shown a machine or mechanism 10 in which tabulating 15 cards 11 may be processed in any suitable manner to obtain the desired information. In order to obtain this information, groups of cards are placed in a suitable feed hopper 12 and are fed or passed from the hopper to the machine and are eventually deposited in a suitable 20 stacker pocket or pockets 13.

With the demand for higher and higher operating speeds in card processing equipment, the standard card feed comprising reciprocating picker knives 14 which are reciprocated in slides substantially parallel to the card 25 stack and generally represented in Figs. 5 to 7 develop serious limitations. While pickers of this type perform reasonably satisfactorily at low feed speeds and up to speeds of 500 to 700 cards per minute under ideal conditions with substantially straight cards, it is obvious 30 from an inspection of these figures that when operating at speeds approaching 1,000 cards per minute or better deck instability or card bounce in the stack becomes a serious problem, particularly if the cards are warped or curled across their width. Since the cards in the hopper 35 are physically moved upwardly by the picker with each forward stroke and lowered by gravity with each return stroke, when the standard picker is reciprocated at speeds over 700 to 800 cards per minute the impulses transmitted to the stacked cards cause them to bounce at a relatively 40 high rate and under certain conditions the stack may start to vibrate or bounce in resonance which, of course, accentuates the bounce or displacement. The point at which this occurs is difficult to predict because of many variables, such as, for example, the direction of card 45 curl, new cards, worn and warped cards, and so forth.

When the bounce reaches a certain magnitude, the picker knife may miss the rear edge of the bottom card, this results in machine stoppage and the operator is then required to manipulate switches or the like to restart the 50 operation. However, due for one reason to the fact that the cards normally rest on the picker slides, what occurs quite often is the cards are rocked and the forward edge of the bottom card may be displaced so that when the rear edge of the card is picked, the bottom card is 55 jammed against the throat knife and is damaged or destroyed. Several cards may be thus mutilated before the machine is stopped. This of course is a troublesome problem and is time consuming.

Accordingly, it is to overcome the above-enumerated 60 disadvantages of the reciprocating card picker at high speed operation that this invention is particularly directed. Referring specifically to Figs. 2-4, a suitable frame construction 15 is provided to support all of the mechanism required to accomplish the card processing 65 operation. The card hopper 12 includes a forward or front wall 16 spaced from a bottom wall 17 to define a throat passage 18, end walls 19, only one of which is shown, and a rear wall defined by a pair of upwardly extending guide posts 21 secured to a supporting bar 22. 70 With the exception of the bottom wall 17, these walls cooperate to receive and hold the stack of cards 11 in position. At the lower central portion of the front

wall 16 is a throat knife 23, against which the cards above the bottom card are urged to prevent the passage of more than one card at a time through the throat passage 18. Disposed slightly more than a card thickness directly below the throat knife 18 is a throat roller or supporting means 24 journaled in a suitable structure 25 to support the central forward edge of the cards in spaced relation to the bottom 17. Thus, as the bottom card is advanced, it passes over the roller 24 through the throat passage 18 to a pair of feed rolls 26 and 27 mounted on feed roll shafts 28 and 29, respectively.

The means for driving the feed rolls and other apparatus includes a drive shaft 31 connected through suitable means to drive motor (not shown). The drive shaft 31 carries a gear 32 meshing with a gear 33 on the lower feed roll shaft 28 and the upper feed roll shaft 29 is rotated through suitable gearing 34 connected to the lower feed roll shaft 28 to provide an upper feed roll peripheral velocity equal to that of the lower roll. The peripheral velocity of the feed rolls are synchronized with the card picker to translate the card for processing at the desired rate. By providing an upper feed roll of smaller diameter both rolls may be disposed closely adjacent the card passage 18. This is more clearly shown in Fig. 2 wherein the lower edge of the front wall 16 of the hopper and the forward portion of the lower wall 17 are slotted to receive the outer peripheral rim portions of the upper and lower rolls, respectively. While the rims of the rolls are disposed in the slots, they do not contact the stacked cards.

At the rear portion of the bottom wall 17 of the hopper are a pair of parallel spaced forwardly directed slots 35 in each of which is closely mounted a card feed unit 36. Each card feed unit includes a picker knife swivel block or head 37 having forward and rear ends and an upwardly tapering top surface 39 terminating in a feed knife edge 41 which extends parallel to the rear edge of the cards and is adapted to engage the bottom card to translate the same forwardly to the first pair of feed rolls. The head 37 is tapped to provide a bore 42 and is mounted to swivel about the axis of an adjustable post or stud member 43 which in turn is rigidly secured to the upper and outer head end 44 of a rocker arm 45. The rocker arms have their lower ends 46 securely clamped to a rocker shaft 47 which defines a rocker arm pivot axis and is journaled in a pair of spaced bearings 48, only one of which is shown, carried in the frame structure 15. The pivot axis of the rocker shaft 47 is positioned at a distance below the hopper to provide an arc comparable to the maximum card warp allowable and at a point closely adjacent a projected line extending from the rear edge of the cards for reasons to be hereinafter described. By axially adjusting the swivel bolts 43, the relative position of the feed knives may be adjusted to compensate for slight misalignment of the various elements.

Secured to the driving shaft 31 to rotate therewith are a pair of cams 49. Each cam engages and operates the free end of a cam follower 51, the followers having their opposite ends secured to the rocker arm shaft 47. Each cam follower 51 rides on its respective cam surface and is closely positioned with respect thereto so that as the drive shaft 31 is rotated, the cams 49 positively drive the rocker shaft 47 to oscillate the rocker arms 45 and the picker heads 37 in an arc about the pivot axis during both the forward and return strokes. The cams define the limit of arcuate travel of the picker and their use with the cam followers at high speed reduces clearance and back lash of the elements to a minimum and thus insures accurate timing of the picker knife with respect to the other apparatus. At lower operating speeds the feed stroke need only be cam operated while the return stroke may be accomplished by other means such as a spring or the like.

Extending from the rear edge of each picker knife

and secured to the picker head 37 to form a portion of the rear end thereof is a U-shaped metal member 52 providing a backwardly and downwardly tapering top surface 53 which as adapted to support the card stack during a portion of the forward and reverse strokes of the picker knife edges 41. This support takes place after the bottom card is picked on the forward stroke and just prior to the positioning of the picker knife at the rear edge of the card on the return stroke. The taper of this movable card support 53 is such that its outer peripheral dimensions remain within the arc described by the picker knife edges 41. With a construction of this type, a portion of the card support always remains at a substantially constant distance from the pivot axis. Openings 54 may be provided in the support 52 to permit access to the picker head supporting bolts 43. It has been found that to accommodate various degrees of card warpage the rear card support surface should preferably be a cord of the described arc between the feed knife edge and trailing edge of the support. By supporting the card stack in this manner during portions of the feed stroke, direct wear on the upper surface of the feed knives is reduced considerably.

The rear wall of the hopper comprising the pair of upright card posts 21 have their lower portions recessed at 55 adjacent the picker heads 37 to provide clearance for the supporting plates 52 during the return stroke of the picker knives. In addition, the trailing edge of the supports 52 are of such length as to not entirely leave the recesses 55 at the end of the forward stroke. The slots 35 in the base member are likewise closed at all times by means of the upper head portions 44 of the rocker arms and the picker knife heads 37. Thus, as the picker knives are oscillated in an arc, the slots in the base and recesses in the posts are always substantially covered or sealed at all times against the entrance of large objects. This eliminates the danger of injury to the operator should his finger be placed near the slots 35 in the base or recesses 55 during reciprocation of the picker knives when the hopper is empty.

By referring to Figs. 2 and 4, it can be seen each feed knife edge 41 is at the apex of two oppositely tapering surfaces, the rear card support surface 53 tapers backwardly and downwardly with respect to the oscillatable feed head axis while the forward card surface 39 including the top surface of the free end 44 of the rocker arm slopes downwardly and forwardly toward the base 17 of the hopper. Also, that each feed knife edge 41 and its forward support 39 is disposed above the bottom wall 17 of the hopper 11 as are the throat rollers 24. Thus, when cards are placed in the hopper 12, the forward portion rests on the throat rollers 24 and the rear portion rests on either the forward or rear card support 39 and 53, respectively, of the picker heads and they do not contact the bottom wall 17 of the hopper. In this manner the weight of the card stack is carried by the rocker shaft bearings 48 and should the cards be curled in a concave direction, they do not rest on the bottom wall 17 but lie on the forward, upwardly tapering picker support 39 at the proper angle for picking. Should the cards be warped or curled longitudinally, the picker heads 37 automatically swivel about their respective posts to accommodate for such warp.

In operation, the operator places a stack of cards 11 in the hopper 12 to rest on the throat roller 24 and picker heads 37, places the standard weight member 56 on the top card and initiates the card processing operation through suitable control means (not shown). As the machine begins to operate, the drive shaft 31 is rotated at the desired speed which in turn rotates the feed rollers 26 and 27, respectively, through the gearings 32 and 34, respectively, and oscillates the rocker arms 45 and the picker heads 37 carried thereby in an arc through the cam followers 51 in timed relation. At the outermost limit of arcuate travel of the feed knives, the knives

reach zero speed and this represents their substantially maximum vertical displacement from the pivot axis as provided by the rocker shaft 47. Starting from this point of zero speed, the card stack is supported on the forward supporting surfaces 39 and as the feed knife edges 41 are moved inwardly by the cam followers 51, they engage the rear edge of the bottom card at a very slight upward angle at relatively low velocity, in the range of 9 inches per second, after which the velocity is uniformly increased at a very rapid rate. It can be seen that as this initial acceleration occurs, the weight of the stack holds the bottom card in position. After this interval the rear edge of the picked card is moved inwardly and downwardly toward the bottom wall 17 without interference therefrom and this action forces the forward end of the card through the throat 18 to engage the first pair of feed rolls 26 and 27, respectively. At the point of engagement with the feed rollers, the card is moving at its maximum velocity which is approximately the same velocity as the feed rollers. For example, at a feed rate of 1,000 cards per minute the velocity of the card at the point of leaving the picker knife is approximately 67 inches per second. At the point of roll pickup, the rotating cams 49 slow down and stop the arc feed knives and start reversal of the stroke.

During the interval when the bottom card is being translated forwardly, the rearwardly tapering card supports 53, carried at the trailing edge of the feed knife edges, are moved in under the rear edge of the next card and they support the stack at a substantially uniform distance from the pivot axis, regardless of the distance of travel of the feed heads 37. In this manner frictional forces normally provided by the weight of the stack after initial acceleration do not interfere with the bottom card movement. Upon the return stroke of the feed knives, the rear card supports 53 continue to hold the stack in this substantially uniform position until the feed knife edges pass beyond the rear edge of the cards. At this point the stack drops by gravity on the forward supporting surface 39, placing the rear edge of the bottom card adjacent the picker knives. The remaining cards are consecutively fed in like manner.

By referring to Figs. 8 to 10, it can be seen that with the use of an arc type card picker as disclosed and tapering or relieving the rear card support 53 to stay within the arc described by the feed knife edge 41, card bounce is reduced to a minimum within wide limits of card curl and other conditions. By maintaining the bottom wall 17 of the hopper spaced from the supporting means the forward edge of the cards will remain on the throat roller 24 so that the stack may pivot about this point during the card feeding operation. This prevents jamming of the cards against the throat knife 23.

The pronounced reduction in card bounce under three typical operating conditions is even more evident when these figures are compared to Figs. 5 to 7 which, as mentioned previously, disclose cards under similar conditions using the standard reciprocating card feed. By comparing Figs. 5 to 10, it can be seen card bounce has been reduced from .180 to .045 inch with $\frac{1}{8}$ inch convexly curled cards; has been reduced from .210 to .045 inch with cards having concave curl of $\frac{1}{8}$ inch; and has been reduced from .030 to .025 when feeding straight cards. In the specific example disclosed, the feed knife is oscillated in an arc having a radius of approximately $2\frac{3}{8}$ inches and the pivot axis is approximately $\frac{1}{8}$ inch inward from a line projected from the rear edge of the stacked cards.

With respect to upper limits of card feeding speeds, the arc type picker described is capable of speeds over 2,200 cards per minute with straight and curled cards without failure. In addition, due to the control of the velocity at the point of card picking, damage to the rear edge of the cards has been practically eliminated. The

above is well beyond the upper limits of the reciprocating pickers under similar card conditions.

In the above examples only static conditions are considered and it is evident that when high speed operation and various inertia forces are considered, card bounce would actually be considerably higher. Thus, with the dependance on gravity return at high picker speeds, it can be readily understood why card misses occur with the reciprocating card picker. In cases where the card stack is supported by the reciprocating picker slides and the incident of rocking occurs, the forward edge of the bottom card may be elevated to the degree where it engages the throat knife at the time of picking and be destroyed or damaged.

10 15 In the above description high picker speed has been stressed, however, it is to be understood the arc type picker may be used at low feed speeds equally as well for the same reasons. In addition, at low speed operation with the removal of the return cam and cam follower 20 a cost reduction is realized when compared to the standard reciprocating picker. At high speeds the initial cost is substantially the same, however, a reciprocating picker wears rapidly and will require frequent replacement. Thus, when compared over a long period of use and low 25 maintenance cost the arc picker is superior in this respect also.

From the above, it can be seen that when feeding cards at high speeds, card stack bounce has been reduced to a minimum value and this reduction in card bounce has 30 proved in actual practice to have practically eliminated card picking failures or card jamming at the throat knife. Also with a card picker of this type, damage to the rear edge of the card has been practically eliminated because the card picker is moving at a substantially low speed at 35 the time of picking and from this point the picker smoothly and quickly accelerates the card to maximum velocity without eccentric impulses applied thereto and with a minimum of frictional interference, or none, from the card stack.

40 45 While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

- 50 1. A card feed for consecutively advancing stacked cards from a hopper, comprising a head having a forward and a rear edge and a top surface, a feed knife edge formed on said top surface intermediate said ends, said top surface being relieved from said feed knife edge 55 toward both ends to provide a forward and rear card supporting surface, a rocker arm mounted to pivot on an axis adjacent a line projected from the rear edge of said cards, means for mounting said head on said rocker arm to provide for swivel movement on an axis normal to said feed knife edge, and means for operating said rocker arm to oscillate said feed knife edge in an arc to advance the cards, said rear supporting surface supporting the unpicked cards at a substantially uniform distance from the rocker arm axis during the forward and reverse 65 stroke of said feed knife edge.
2. A card feed for consecutively advancing aligned stacked cards from a hopper, comprising a head member having an upper surface, a feed knife edge formed on said upper surface defining the outermost projection of said head and extending parallel to the rear edge of the cards to engage the same, a rocker arm pivoted to oscillate on an axis adjacent a line projected from the rear edge of the stacked cards, means for securing said head member to the upper end of said rocker arm, said last-named means including a connection to journal said head mem- 70 75

ber for swivel movement on an axis transverse to the rocker arm axis, means for oscillating said rocker arm in an arc about said axis, to move said feed knife edge into contact with the rear edge of the bottom card at such an angle to maintain the stack against the bottom card during initial acceleration of the same, and a rearwardly projecting card support secured to said head member in back of said feed knife edge to support the unpicked cards during the forward stroke of said feed knife edge but after the initial acceleration of the picked bottom card, said support being tapered with respect to said axis to remain within the arc described by said feed knife edge.

3. A card feed for consecutively advancing stacked cards from a hopper, comprising a head member having a forward and a rear end and a top surface, a feed knife edge disposed on the top surface of said head intermediate said ends, said top surface being tapered downwardly from said feed knife edge toward both ends to provide a forward and a substantially flat rear card supporting surface, a rocker arm mounted to pivot about an axis disposed inwardly from but adjacent a line projected from the rear edge of the stacked cards, means for securing said head member to said rocker arm, said last-named means including a journal connection to provide swivel movement of said feed knife edge about an axis transverse to said rocker arm axis, and means for oscillating said feed knife edge in an arc by said rocker arm to advance the cards, said feed knife edge moving into contact with the rear edge of the bottom card at such an angle to maintain the stack on the bottom card during initial acceleration of the same, said flat rear card supporting surface holding the unpicked cards at a substantially uniform distance from said rocker arm axis after initial acceleration of the forward stroke and during the reverse stroke of said feed knife edge.

4. A card feed for consecutively advancing stacked cards from a hopper, comprising a head member having a top surface, a feed knife edge formed on said top surface and defining the outermost projection of said head member, a rocker arm mounted to pivot about an axis adjacent a line projected from the rear edge of the stacked cards, means for securing said head member to the free end of said rocker arm for movement therewith, said last-named means including a journal connection to provide for rocking movement of said head member on an axis transverse to said rocker arm axis, means for oscillating said rocker arm in an arc about said axis between zero and maximum velocities to move said feed knife edge into contact with the rear edge of the bottom card at a relatively low velocity and at such an angle to maintain the stack against the card during initial acceleration of the same, and a rearwardly directed projection defining a card support secured to said head member in back of said feed knife edge for supporting the cards in said hopper after the initial acceleration of the forward stroke and during the reverse stroke of said feed knife edge, said card support being tapered with respect to the rocker arm axis to support the unpicked cards at a substantially uniform distance from the rocker arm axis.

5. In a card feeding unit, the combination of a hopper for receiving stacked cards and having a lower, forward throat section through which cards are consecutively translated, a card feed head including a feed knife edge for engaging the rear edge of the lower card and a rearwardly projecting card support behind said feed knife edge for supporting the rear portion of the stacked cards, a rocker arm disposed below said hopper pivoted to oscillate about an axis substantially in alignment with a line projected from the rear edge of the stacked cards, means for securing said card feed head to the upper free end of the said rocker arm to position the feed knife edge at the rear edge of the cards when the rocker arm is adjacent its uppermost limit of travel, said last-named means including a journal connection to provide for rocking move-

ment of said card feed head and card support on an axis transverse to said rocker arm axis, and means for oscillating said card feed head in an arc about the rocker arm axis whereby the rear edge of the picked card is moved in a forward and downward direction, said card support being tapered inwardly with respect to the rocker arm axis and movable with said card feed head below the stack to support the same at a substantially uniform distance from the rocker arm axis to minimize bouncing of the stacked cards during oscillation of said card feed head.

6. In a card feeding unit, the combination of a hopper for receiving stacked cards and having a lower forward throat section through which cards are consecutively translated, a card feed head including a feed knife edge for engaging the rear edge of the lower card, a rocker arm disposed below said hopper pivoted to oscillate about an axis substantially in alignment with a line projected from the rear edge of the stacked cards, means for securing said card feed head to the upper free end of the said rocker arm to position the feed knife edge at the rear edge of the cards when the rocker arm is adjacent its uppermost limit of travel, said last-named means including a journal connection to provide for swivel movement of said card feed head on an axis transverse to said rocker arm axis, means for oscillating said card feed head in an arc about the rocker arm axis between zero and a maximum velocity so that the feed knife edge engages the rear edge of the picked card at a relatively low velocity and at such an angle to maintain the weight of the stack on the bottom card during initial acceleration of the same after which the card is moved in a forward and downward direction, and a rearwardly and downwardly projecting portion defining an upper card support surface secured to said card feed head behind said feed knife edge for supporting the rear portion of the stacked cards after the initial acceleration of the forward stroke and during the reverse stroke of the feed knife edge, said upper card support surface being defined by the cord of an arc projected from said feed knife edge inwardly therefrom with respect to the rocker arm axis to support the stacked cards at a substantially uniform distance from the rocker arm axis to minimize card bounce during oscillation of said card feed head.
7. In a card feeding unit, the combination of a hopper including a base portion for receiving stacked cards and having a lower forward throat section through which cards are consecutively translated, means for supporting a portion of the forward edge of the bottom card at the throat section out of contact with said base, a card feed head including a feed knife edge for engaging the rear edge of the lowermost card and a rearwardly projecting portion defining a card support behind said feed knife edge for supporting the rear portion of the stacked cards out of contact with said base, a rocker arm disposed below said hopper pivoted to oscillate about an axis substantially in alignment with a line projected from the rear edge of the cards, means for securing said card feed head to the upper free end of said rocker arm to position the feed knife edge at the rear edge of the cards when the rocker arm is adjacent to its uppermost limit of travel, said last-named means including a journal connection to provide for swivel movement of said card feed head on an axis transverse to said rocker arm axis, and means for oscillating said card feed head in an arc about the rocker arm axis between zero and maximum velocities so that the feed knife edge engages the rear edge of the picked card at a relatively low velocity and at such an angle to maintain the stack against the bottom card during initial acceleration of the same after which the picked card is moved in a forward and downward direction toward said base, said rearwardly directed card support being tapered toward the pivot axis so that the remaining cards are supported thereby at a substantially uniform distance from

the rocker arm axis to minimize bouncing of the stacked cards during oscillation of said card feed head.

8. In a card feeding unit, the combination of a hopper including a base portion for receiving aligned stacked cards and having a lower forward throat section through which cards are consecutively translated, means for supporting a portion of the forward edges of the cards at the throat section out of contact with said base, a card feed head including a feed knife edge for engaging the rear edge of the lowermost card and a rearwardly projecting portion defining a card support behind said feed knife edge for supporting the rear portion of the cards out of contact with said base, a rocker arm disposed below said hopper secured to a rocker arm shaft to oscillate about an axis substantially in alignment with a line projected from the rear edge of the cards, bearing means for supporting said rocker arm shaft, means for securing said card feed head to the upper end of said rocker arm, said last-named means including a journal connection to provide for rocking movement of said card feed head on an axis transverse to said rocker arm axis, and means for oscillating said rocker arm and said card feed head in an arc about its axis whereby the rear edge of the engaged lowermost card is moved in a forward and downward direction toward said base while the remaining cards are supported on the card support at a substantially uniform distance from said shaft axis to minimize displacement of the stacked cards during oscillation of said card feed head, said rocker arm shaft bearings providing the sole support for the rear portion of the aligned card stack.

9. In a card feeding apparatus, the combination of a hopper having front, side and bottom walls and a guide member including a recessed portion defining a rear wall, said bottom wall being slotted adjacent the recessed portion of said guide member, a feed head member including a card feed knife edge thereon disposed in said slotted portion of said bottom wall and having a rearwardly ex-

tending section projecting in the recessed portion of said guide member, a rocker arm mounted to pivot about an axis, means for securing said feed head member to said rocker arm, and means for oscillating said rocker arm and said feed head member in an arc, said feed head member and rearwardly projecting extension maintaining the slot in said bottom wall and the recessed portion of said guide member covered at both extremes of movement of said oscillatable rocker arm.

10. In a card feeding apparatus the combination of a hopper having front, side and bottom walls and guides defining a rear wall, each of said guides having a lower recessed portion, said bottom wall being slotted adjacent the recessed portion of each of said guide members, a card feed head including a card feed knife edge thereon disposed in each of said slotted portions and having a rearwardly extending section projecting into the recessed portion of said guide members, rocker arms mounted to pivot about an axis, an upper end portion carried by each of said rocker arms disposed in each of said slots, means for securing one of said card feed heads to the upper end portion of each rocker arm, and means for oscillating said rocker arms and said card feed heads in an arc, said upper end portions, associated card feed heads and rearwardly directed extensions cooperating to maintain the related slots in said bottom wall and the adjacent recessed portion in said guide members closed at both limits of arcuate travel of said rocker arms.
